ABSTRACT

'NCCO1' is a new cultivar of smokebush is disclosed,
characterized by a compact habit, dark purple foliage, and
large, purple inflorescences. The new variety is a *Cotinus coggygria*, typically produced as an outdoor ornamental
plant.

4 Drawing Sheets

1

Latin name of the genus and species: *Cotinus coggygria*.
Variety denomination: 'NCCO1'.

BACKGROUND OF THE INVENTION

The present invention comprises a new and distinct
smokebush cultivar hereinafter referred to by the cultivar
name 'NCCO1'. This new smokebush was developed
through a breeding program at Mills River, N.C. 'NCCO1'
was selected from a population of seedlings grown from an
open-pollinated, unnamed, *Cotinus coggygria*. The first
asexual propagation of 'NCCO1' was carried out in July
2009 by rooting stem cuttings at a research nursery in Mills
River, N.C. and has been asexually reproduced repeatedly
by vegetative cuttings and tissue culture over a 8 year
period. 'NCCO1' roots from softwood cuttings treated with
a basal dip of 6,000-8,000 ppm indole butyric acid (potas-
sium salt) in water. 'NCCO1' has been found to retain its
distinctive characteristics through successive asexual propa-
gations.

SUMMARY OF THE INVENTION

The following are the unique combination of character-
istics of this new cultivar when grown under standard
horticultural practices at North Carolina State University,
Mountain Horticultural Crops Research Station, Mills River,
N.C.

1. Compact habit.
2. Dark purple foliage.
3. Large, purple inflorescences.

2

COMPARISON WITH PARENT VARIETY

Plants of the new variety are similar to plants of the parent
in most horticultural characteristics. 'NCCO1' differs how-
ever, in the following:

1. More compact plant habit than the parent.
2. Larger inflorescence than the parent.
3. Darker purple foliage than the parent.

**COMPARISON WITH COMMERCIAL
CULTIVAR**

'NCCO1' is distinguished from the commercial cultivar
15 *Cotinus coggygria* 'Velvet Cloak', unpatented in that
'NCCO1' has a more compact habit and will grow to be 2
meters tall by 2 meters wide with moderate pruning. *C.
coggygria* 'Velvet Cloak' will grow to be taller than 3 meters
with similar pruning. 'NCCO1' has dark Greyed-Purple
20 (N186A) mature foliage and darker Greyed-Purple (187A)
inflorescence panicles compared to *C. coggygria* 'Velvet
Cloak' with Greyed-Purple (N186D) foliage and lighter-
colored Greyed-Purple (183B) inflorescence panicles.

BRIEF DESCRIPTION OF THE DRAWINGS

This new smokebush is illustrated by the accompanying
photographs which show the plant's form, foliage and
30 inflorescences. The colors shown are as true as can be
reasonably obtained by conventional photographic proce-
dures. Colors in the photographs may differ slightly from the

color values cited in the detailed botanical description, which accurately describe the colors of the new smokebush.

FIG. 1 is a color photograph showing the inflorescence and flowers of 'NCCO1' in spring 2017 on an eight-year-old tree.

FIG. 2 is a color photograph showing the inflorescence and seeds of 'NCCO1' in summer 2016 on a seven-year-old tree.

FIG. 3 is a color photograph showing inflorescences and foliage of 'NCCO1' in summer 2016 on a seven-year-old tree.

FIG. 4 is a color photograph showing the form of 'NCCO1' in summer 2016 on a seven-year-old tree.

DETAILED BOTANICAL DESCRIPTION

5

The following is a detailed description of the botanical characteristics of the new and distinct smokebush variety plant known by the denomination 'NCCO1'. The detailed description was taken on a six-year-old field-grown plant in 20 Mills River, N.C. in 2015. All colors cited herein refer to The Royal Horticultural Society Colour Chart (The Royal Horticultural Society (R.H.S.), London, 2001 Edition). Where specific dimensions, sizes, colors, and other characteristics are given, it is to be understood that such characteristics are approximations or averages set forth as accurately as practicable.

TECHNICAL DESCRIPTION OF THE VARIETY

Classification:

Botanical name.—*Cotinus coggygria* 'NCCO1'.

Common name.—Smokebush.

Parentage: Seedling grown from an open-pollinated *Cotinus coggygria*.

Plant description:

Growth habit.—Upright shrub.

Height.—Approximately 2 m at 6 years.

Width.—Approximately 1.5 m at 6 years.

Shoot and stem:

Shoot color (current year).—Greyed-Purple (187B) flush over Greyed-Green (198A) with mottled spots of Grey-Brown (N199A).

Shoot texture (current year).—Spotted with Grey-Brown (N199D) lenticels.

Shoot diameter (current year).—4 mm (typically ranging from 3 mm-5 mm) at base.

Annual shoot length.—Avg. 10 cm (typically ranging from 6 cm to 14 cm).

Internode length.—Avg. 1 cm (typically ranging from 0.5 cm to 2.0 cm).

Lateral branch length.—Average 63.4 cm (typically ranging from 48.0 to 90.0 cm).

Lateral branch diameter.—Avg. 0.8 cm (typically ranging from 0.3 to 1.3 cm).

Lateral branch texture.—Spotted with Greyed-Green (197D) lenticels.

Stem/trunk diameter (10 cm from base).—10 cm.

Stem/trunk color.—Greenish-Grey (202D) to Brownish-Grey (N200B).

40

45

50

55

60

65

Leaves:

Type.—Simple.

Persistence.—Deciduous.

Arrangement.—Alternate.

Shape.—Obovate.

Apex.—Obtuse to obovate.

Base.—Cuneate.

Margins.—Entire, slightly undulate.

Venation.—Reticulate.

Vein texture.—Glabrous.

Emerging leaves.—Color: Upper: Greyed-Purple (187A) to Dark Purplish-Grey (N187A). Lower: Greyish-Purple (N187B). Vein color: Moderate-Red (185B), both sides. Texture: Glabrous, upper and lower surfaces.

Mature leaves during growing season.—Length of lamina: Avg. 5.2 cm (typically ranging from 3.1 to 7.5 cm). Width: Avg. 3.9 cm (typically ranging from 3.1 to 5.8 cm). Color: Upper: Greyed-Purple (N186A). Lower: Greyed-Purple (N187A). Vein color: Ranging from Red-Purple (61B) to Greyed-Purple (N187A), both sides.

Fall color.—Upper: Combination of Greyed-Orange 169B, Red 46C and Greyed-Orange N163B. Lower: Combination of Greyed-Orange 169B, Red 46C and Greyed-Orange N163B. Vein color: Ranging from Greyed-Orange 169B and Greyed-Orange N163B, both surfaces. Texture: Glabrous.

Leaf attachment.—Petiolate.

Petiole.—Length: Avg. 2.9 cm (typically ranging from 1.3 to 4.0 cm). Diameter: About 0.1 cm. Color: Greyed-Purple (183B). Texture: Glabrous.

Inflorescence:

Flower arrangement.—Terminal panicle.

Inflorescence type.—Panicle or thyrsse.

Inflorescence length/height.—Avg. 17.4 cm (typically ranging from 12.0 to 20.5 cm).

Inflorescence width.—Avg. 15.5 cm (typically ranging from 13.0 to 17.0 cm).

Inflorescence aspect.—Upward and outward.

Individual flowers per panicle.—Approximately 300.

Flowering season.—Spring; May in Mills River, N.C.

Lastingness.—Flowering begins first week of June in Michigan. flowerless panicles persist until early August.

Flower bud.—Shape: Oblong. Length: About 0.15 cm. Width: About 0.10 cm. Color: Closest to Greyed-Purple (187A).

Flower.—Shape: Rotate. Height: About 0.2 cm. Width: About 0.5 cm.

Petal.—Arrangement: Rotate. Number: 5. Fused: Not fused. Shape: Ovate. Margin: Entire. Apex: Acute. Base: Cuneate. Length: About 0.2 cm. Width: About 0.15 cm. Color: Closest to Yellow-Green (150C). Texture: Glabrous.

Calyx.—Shape: Campanulate. Length: About 0.1 cm. Diameter: About 0.3 cm.

Sepal.—Arrangement: Rotate. Number: 5. Shape: Ovate. Margin: Entire. Apex: Acute. Base: Cuneate. Length: About 0.1 cm. Width: About 0.1 cm. Color: Closest to Yellow-Green (144C). Texture: Glabrous.

Peduncle.—Length: Avg. 17.4 cm (typically ranging from 12.0 to 20.5 cm). Diameter: Avg. 0.2 cm (typically ranging from 0.1 to 0.2 cm). Color: Greyed-Purple (187A). Texture: Glabrous.

Pedicels.—Flowered pedicel: Length: Avg. 0.6 cm (typically ranging from 0.1 to 1.2 cm). Width: Less than 0.1 cm. Color: Greyed-Purple (187A). Texture: Pubescent. Flowerless pedicel: Length: Avg. 0.8 cm (typically ranging from 0.3 to 1.7 cm). Width: Less than 0.1 cm. Color: Greyed-Purple (187A). Texture:

US PP30,216 P2

5

Densely pubescent. Hairs approximately 1 mm, colored near Greyed-Purple 183A.

Reproductive organs:

Gynoecium.—Pistil number: 1. Pistil length: About 0.02 cm. Stigma shape: Club-shaped. Stigma color: 5 Yellow-Green (144B). Style length: About 0.01 cm. Style color: Yellow-Green (144B). Ovary color: Yellow-Green (144B).

Androecium.—Stamen number: 5. Anther shape: Kidney-shaped. Anther length: About 0.03 cm. Anther color: Yellow-Orange (15A). Filament length: About 0.1 cm. Amount of pollen: Low. Pollen color: Yellow-Orange (15A).

Fruit and seed:

Fruit type.—Drupe.

Fruit length.—About 0.3 cm.

6

Fruit diameter.—About 0.5 cm.

Fruit color.—Greyed-Purple (N186A).

Fruit texture.—Glabrous.

Seed number.—1 seed per fruit.

Seed length.—About 0.3 cm.

Seed diameter.—About 0.5 cm.

Seed color.—Grey-Brown (199C).

Disease and insect resistance: No significant disease or insect pests have been observed.

10 Cold hardiness: At least USDA zone 6b; testing has not been completed in colder zones.

What is claimed is:

15 1. A new and distinct smokebush plant named 'NCCO1' as illustrated and described herein.
